DESIGN FOR A HOUSING FOR SIGNAL DEVICES

Lloyd Rittenhouse, Honeoye Falls, N. Y., assignor
to The A. E. Rittenhouse Co., Inc., Honeoye
Falls, N. Y., a corporation of New York

Application November 16, 1939, Serial No. 88,328

Term of patent 7 years

To all whom it may concern:

Be it known that I, Lloyd Rittenhouse, a citizen
of the United States of America and residing at
Honeoye Falls, in the county of Monroe and
State of New York, have invented a new, original,
and ornamental Design for a Housing for Signal
Devices, of which the following is a specification,
reference being had to the accompanying draw-
ing, forming a part thereof.

In the drawing:

Fig. 1 is a front elevation of a housing for
signal devices showing my new design;

Fig. 2 is an end elevation of the same, and
Fig. 3 is a plan view of the same.

I claim:

The ornamental design for a housing for signal
devices, as shown.

LLOYD RITTENHOUSE.
